(57) **CLAIM**

The ornamental design for a kneeling platform, as shown and described.

DESCRIPTION

FIG. 1 is a top plan view of the kneeling platform of my new design;

FIG. 2 is a front elevational view thereof;

FIG. 3 is a rear elevational view thereof;

FIG. 4 is a side elevational view of the right side thereof;

FIG. 5 is a side elevational view of the left side thereof; and,

FIG. 6 is a bottom plan view thereof.

The unshaded surfaces shown in FIG. 6 form no part of the claimed design.
